HEEL COUNTER REINFORCEMENT

Joseph Agostinelli, Detroit, Mich.

Application March 29, 1946, Serial No. 658,337

2 Claims. (Cl. 36—68)

1

My invention relates to a new and useful improvement in a heel reinforcement and is adapted for use on footwear and particularly leather footwear such as boots, shoes and the like. Experience has shown that with shoes which are worn a short time, the heel is pressed out of its proper position and sags laterally. This sagging of the heel or counter of the shoe is generally towards the outside of the shoe, in such cases the counter of the heel or shoe does sag towards the inside. When the counter of the heel sags the heel of the wearer is thus thrown out of proper alignment with the remaining portion of the shoe with the result that discomfort is experienced and proper walking prevented.

It is an object of the present invention to provide a reinforcement for a counter in a heel which will prevent the sagging of either side and which will serve to retain the counter and heel portion of the shoe in proper alignment to the remaining portion of the shoe.

Another object of the invention is to the provision of a reinforcement for a heel counter whereby the foot of the wearer will be retained in proper position relatively to the remaining portion of the shoe and excessive wear on the low side of the heel will be prevented.

Another object of the invention is the provision of a bendable portion on a heel counter reinforcement so that it may be bent inwardly to always provide a snug fit of the upper portion of the counter with the foot of the wearer.

Another object of the invention is the provision of a heel counter reinforcement so constructed and arranged that greater comfort in walking may be accomplished.

Other objects will appear hereinafter.

It is recognized that various modifications and changes may be made in the detail of structure illustrated without departing from the invention itself and it is intended that these shall be embraced within the claims which form a part hereof.

Forming a part of this application are drawings in which,

Fig. 1 is a perspective view of the reinforcement,

Fig. 2 is a central sectional view of the invention showing it applied,

Fig. 3 is a sectional view taken on line 3—3 of Fig. 2,

Fig. 4 is a fragmentary sectional view taken on line 4—4 of Fig. 2.

In the drawings I have illustrated the invention applied to a shoe 20 having a heel counter

2

embodying the outer layer 18 and the inner layer 19 and a fiber reinforcement member 30 that embraces the heel or counter of the shoe. As shown in Fig. 2, the portion 22 of the counter 5 is positioned rearwardly on the point 23 at which the counter turns upwardly. The reinforcement comprises a shank or plate 9 formed from rigid material, preferably resilient metal. This shank or plate 9 is positioned to lie between the sole 16 and the sole 17 and is secured in position by suitable securing means projected through the openings 24. The rear end of the body 9 is formed concave as at 25, this concavity being positioned centrally of the body 9 and being 10 adapted to accommodate the in-turned portion of the outer layer 18 of the counter. Projecting outwardly from the rear portion of the body 9 at opposite sides are the tongues 10 and 12, each of these tongues being curved upwardly as 15 at 11 and 13 respectively and lie between the fibre member 30 and outer covering 18. These tongues are cut away on their inner side as at 20 26 so that the upwardly turned portion projects forwardly as clearly shown in Fig. 1 and Fig. 2. 25 These tongues, with the upwardly curved portion, may be termed reinforcement side flaps on the end of the body 9.

It is believed obvious from an examination of Fig. 2, that the member 10 is more easily bendable at its free end than adjacent the end where it is attached to the body 9 and that the farther this distance is projected the more easily bendable becomes the material. Consequently, it will appear obvious that the counter of the shoe is 30 rigidly reinforced adjacent its lower portion so as to prevent lateral sagging while the reinforcement member upwardly thereof may be bent inwardly by pressure of the hand, thus allowing the wearer to bend the upper portion inwardly 35 so that the counter will fit snugly about the heel of the foot.

Experience has shown that a shoe with a heel counter reinforcement of this type mounted 40 therein will be more comfortable to the wearer and that the wearer, because the sagging of the counter is prevented and the wearer's heel is 45 kept in proper alignment to the remaining portion of the shoe, will find more comfort in wearing the shoe and less fatigue in walking.

It will be noted that the side flap or tongue 12 is of less height than the side flap or tongue 10. This lower side reinforcement is positioned on the inner side of the shoe as the tendency 50 to sag inwardly is much less than the tendency

to sag outwardly and less resistance is required on the inner side of the heel counter.

What I claim as new is:

1. A shoe heel counter reenforcement member comprising an elongated rigid body adapted for mounting between the soles of a shoe and extending longitudinally thereof for a portion of the length proceeding forwardly from the heel counter; a reenforcing flap projecting outwardly from opposite sides of said body at the rear end 10 and lying between the inner and outer layers of the heel's counter, one of said flaps being of greater height and length than the other.

2. A shoe heel counter reenforcement of the class described comprising an elongated rigid 15 metallic body formed from resilient material and having one end curved concave and adapted for positioning between the soles of a shoe with the concave end accommodating the in-turned portion of the outer layer of the shoe heel counter; 20 a reenforcing flap projecting outwardly from op-

posite sides of said body adjacent said concave end and thence curved upwardly and projected forwardly the upper portions of said flaps being bendable, said flaps being positioned between the outer and inner layers of the shoe heel counter, one of said flaps being of greater height and length than the other.
